UNITED STATES PATENT OFFICE.

PETER G. VAN WIE, OF CLEVELAND, OHIO, ASSIGNOR TO JOHN V. KENNEDY,
OF SAME PLACE.

DOPE-CUP.

SPECIFICATION forming part of Letters Patent No. 432,100, dated July 15, 1890.

Application filed October 23, 1889. Serial No. 327,947. (No model.)

To all whom it may concern:

Be it known that I, PETER G. VAN WIE, a citizen of the United States, and a resident of Cleveland, county of Cuyahoga, and State of Ohio, have invented certain new and useful Improvements in Dope-Cups, of which the following is a specification, the principle of the invention being herein explained, and the best mode in which I have contemplated applying that principle, so as to distinguish it from other inventions.

My invention relates to dope or grease cups; and it consists of improvements hereinafter described and claimed.

15 Referring to the drawings, Figure 1 is a central vertical sectional view taken through the dope-cup. Fig. 2 is a view, partly in section and partly in elevation, the piston being shown in raised position.

20 A is the cylindrical body portion of the cup, threaded at its upper portion to engage with the threaded cover B, and provided at its lower portion with the discharge-orifice a and with the opposite screws b, whose inner 25 ends control the discharge area of said orifice. Said discharge area may be regulated by merely turning the screws in or out, as desired. The upper portion of said cover B is provided with the upwardly-projecting threaded 30 portion C, formed integral with the cover itself. Sleeve D has threaded engagement with said projecting portion C, and is provided with the thumb-levers d, by means of which it may be threaded up or down said projecting 35 portion. Said sleeve is further provided with a set-screw d', by means of which it may be securely held or locked in any desired position. Piston E, having a superficial area practically equal to the cross-sectional area

40 of said cylindrical body portion of the cup, is inserted within the cup, and is provided with an annular rabbet e, in which is inserted the metallic spring-packing F, that serves to make tight the joint between the cup and the pis- 45 ton. Piston-rod G is formed integral with the piston and extends upwardly through the usual central opening that is formed in the cover and also formed through the upwardly-projecting threaded portion C. Threaded 50 onto the upper extremity of said piston-rod

is the cap g, that is of sufficient area to cover portion C and sleeve D. Spiral spring H is located intermediate of cover B and piston E. The tension or pressure of said spring serves to force downwardly the piston, which in 55 turn causes the grease to be forced out from the discharge-orifice of said cup.

The operation of the cup is as follows: Let it be supposed that the piston is in the position shown in Fig. 1 and that the spring is 60 relaxed, and that it is desired to fill the cup. Sleeve D is by means of the thumb-lever d turned upwardly on the projection portion C, and as it is forced up it engages with cap g, that is secured to piston-rod G, and as a re- 65 sult the piston is brought into nearer position to the cover and the spring is contracted and compressed until, finally, the piston and spring assume the position shown in Fig. 2, or the piston may be brought into even closer prox- 70 imity to the cover. The cover is now removed from the cup and the screws b are turned up until the proper area of discharge between the inner extremities of said screws is secured. The cup is now filled with grease and the 75 cover is again turned onto the cup. Sleeve D is now threaded down until its lower extremity engages with the cover, as shown in Fig. 1. This permits the force of the spring to be exerted against the piston and the pis- 80 ton to be pressed against the grease contained in the cup. This has a tendency gradually and slowly to force the grease outwardly through the discharge-orifice as may be nec- 85 essary. The pressure of the spring will con- 90 tinue to be exerted until the piston is brought into engagement with the lower portion of the cup and the grease is entirely discharged.

The foregoing description and accompany- 95 ing drawings set forth in detail mechanism in 90 embodiment of my invention. Change may be made therein provided the principles of construction respectively recited in the follow- 95 ing claims are employed.

I therefore particularly point out and dis- 95 tinctly claim as my invention—

1. In a dope-cup, the combination of a cover provided with projecting threaded portion C and having a central opening, a piston and a piston-rod, said piston-rod passing through 100

said cover-opening, and a threaded sleeve D, engaging with the said projecting threaded portion of said cover, also engaging with cap g, secured to said projecting threaded portion 5 and adapted to retain said piston in desired position, substantially as set forth.

2. In a dope-cup, the combination of a cover having a central opening and provided with a projecting threaded portion, a cap secured 10 to its upper extremity, a piston and a piston-rod, said piston-rod passing through said central opening, a spring located intermediate of said cover and piston, said piston provided

with a spring metallic packing and a threaded sleeve engaging with said projecting threaded 15 portion of said cover and also engaging with the cap that is secured to the upper extremity of said piston-rod, substantially as set forth.

In testimony that I claim the foregoing to be my invention I have hereunto set my hand 20 this 30th day of July, A. D. 1889.

P. G. VAN WIE.
